(57) **CLAIM**

The ornamental design for a vomit bag as shown and described.

DESCRIPTION

FIG. 1 is a front, right, and top perspective view of a vomit bag, showing my design.

FIG. 2 is a rear, left, and bottom view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of an area labeled 9 in FIG. 1; and,

FIG. 10 is a perspective view showing the vomit bag in a usable state.

The broken lines depict portions of a vomit bag and portions of a human form that form no part of the claim.

The dot-dash broken lines in FIGS. 1 and 9 depict the boundaries of the enlargements that form no part of the claimed design.
